UNITED STATES PATENT OFFICE.

ARTHUR C. BAUMWART, OF LAWLER, IOWA, ASSIGNOR OF TWO-THIRDS TO
GIDEON W. BAUMWART AND GRANT E. BAUMWART, BOTH OF SAME
PLACE.

GATE.

SPECIFICATION forming part of Letters Patent No. 430,507, dated June 17, 1890.

Application filed February 15, 1890. Serial No. 340,625. (No model.)

To all whom it may concern:

Be it known that I, ARTHUR C. BAUMWART, a citizen of the United States of America, residing at Lawler, in the county of Chickasaw 5 and State of Iowa, have invented certain new and useful Improvements in Gates; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

This invention has reference to tilting and 15 folding gates; and it consists in the improved construction hereinafter described and set forth, whereby a simple and efficient arrangement is provided that will enable the gate to be conveniently opened from either side and 20 insure the several wires and parts forming the gate proper swinging upward, so that all the parts are maintained taut and in proper position.

In the accompanying drawings, forming 25 part of this specification, Figure 1 is a perspective view of a gate embodying my improvements, the same being represented in a closed position. Fig. 2 is a side view, the operating-lever and its standard being removed 30 to more clearly show the gate in its elevated position. Fig. 3 is a sectional plan view.

The oppositely-arranged posts A B are located on either side of the roadway, and the post B is that to which the gate is to be hung. 35 The said gate consists of a central portion C, comprising parallel bars *a a* and outer longer bars *b b*, the former being slightly spread in the direction of the post B, while the latter diverge considerably toward their 40 rear ends. At about the point where the outer ends of said bars *a a* terminate the bars *b b* are bent closely parallel, and are intermediately braced by a filling-piece *c*. Between the outer ends of the bars *b b* is pivotally hung the outer upright D, on the inner side of which above and below its pivotal connection wires *d d* are connected and attached at their other ends to the face of the post B. Loops *e e* are located on the face of

the post B and support a transverse rod *f*, to 50 the ends of which bars *a b* are connected, the latter supporting between them receptacles F, adapted to be weighted to counterbalance the gate in its movements.

At either side of the post B a standard E 55 is located for the pivotal support of an extended lever F', the outer end of which is normally elevated to a considerable degree and has depending therefrom a cord or cable, so that it may be operated by a person on the 60 ground or on any suitable vehicle. The ends of the levers being centrally over the roadway, they are conveniently operated. From the rear side of the post B, adjacent to the base thereof, projects a bracket *f'*, to which 65 pulley-blocks I are connected, around the pulleys of which pass cables *h*, connected to the receptacles F, the other ends of said cables being connected to the outer ends of links *i*, pivotally attached at their inner ends 70 to the post B. The outer ends of the links *i* are connected each to the inner end of the adjacent lever F' by a short cable *x*. A short transverse wire *j* carries at each end a ring, through which one of the cables *h* passes, 75 and attached to each of said rings is a longitudinal wire *j'*, extending over pulleys *l* between the adjacent receptacle and the post, after which both wires *j' j'* merge into a single strand *k'*, which is connected to the latch *x'*. 80

The post A carries on its inner side upper and lower clips *k k*, which prevent all lateral movement of the gate when in position and insure the upright's descending to its proper position. 85

In operation, a person approaching the gate from either side depresses the free end of the lever on that side, thus exerting traction on the receptacles F to effect their descent to raise the gate, the central strand releasing 90 the latch and bracing all the parts during movement of the gate. It will be noted that as the portion C ascends the upright maintains a vertical position at all times, so that the wires composing the rest of the gate are 95 maintained taut. When the gate has been raised to a certain height, the weight of the receptacles will cause it to move to a vertical

position, and the bars *a a* of the central portion will rest against the cross-bar on top of post B, these bars keeping the gate in a vertical position, the several wires and the upright folding parallel with the portion C. When the opposite side of the gate is reached, a pull on the lever will vibrate the parts and cause the gate to overcome the weight of the receptacles and descend to its first position.

10 The construction and arrangement of the gate is such that it may readily be raised and lowered by hand.

I claim—

1. The combination, with a fixed post, of a swinging and folding gate consisting of portion C, pivoted on the post and provided with weighted receptacles, as described, an upright centrally pivoted on the outer end of portion C, upper and lower wires connecting said upright and fixed post, the wires *j j'* *k'*, cables *h x*, link-bars *i*, and lever devices

having said cables connected therewith for vibrating said portion C on its pivot, substantially as set forth.

2. The combination, with a fixed post B, of a gate consisting of portion C, hung on said post and provided with weighted receptacles, an upright pivoted in the outer end of portion C, upper and lower wires connected to said upright and to the post B, together with pivoted levers, bracket-pulleys, pivoted link-bars *i*, cables *h x*, connecting-levers, link-bars, and weights, and wire connected to said cables and extending to and connected with the spring-latch, substantially as set forth.

35

In testimony whereof I affix my signature in presence of two witnesses.

ARTHUR C. BAUMWART.
